US00D783857S

(12) **United States Design Patent** (10) **Patent No.:** **US D783,857 S**
(45) **Date of Patent:** **** Apr. 11, 2017**

(54) **MODULAR BUILDING**

(71) Applicants: **Peter E. Gill**, Tamuning, GU (US);
Peter E. Gill, III, Tamuning, GU (US)

(72) Inventors: **Peter E. Gill**, Tamuning, GU (US);
Peter E. Gill, III, Tamuning, GU (US)

(**) Term: **15 Years**

(21) Appl. No.: **29/547,997**

(22) Filed: **Dec. 9, 2015**

Related U.S. Application Data

(63) Continuation-in-part of application No. 14/221,335, filed on Mar. 21, 2014, which is a continuation-in-part of application No. 14/143,057, filed on Dec. 30, 2013, now abandoned, which is a continuation-in-part of application No. 13/870,141, filed on Apr. 25, 2013, now Pat. No. 8,640,396.

(57) **CLAIM**

The ornamental design for a modular building, as shown and described.

DESCRIPTION

FIG. 1 is a top perspective view of a modular building incorporating our new design;

FIG. 2 is a bottom perspective view of a modular building;

FIG. 3 is a front view of a modular building;

FIG. 4 is a left side or right side view of a modular building;

FIG. 5 is a top plan view of a modular building; and,

FIG. 6 is a bottom plan view of a modular building.

The broken lines shown in the drawings illustrate portions of the modular building that forms no part of the claimed invention.

1 Claim, 6 Drawing Sheets
